UNITED STATES PATENT OFFICE.

AHIJAH COSSEL, OF WAYNE, MARION COUNTY, INDIANA.

PORTABLE STRAW-STACKER.

SPECIFICATION forming part of Letters Patent No. 284,280, dated September 4, 1883.

Application filed September 28, 1880. (No model.)

To all whom it may concern:

Be it known that I, AHIJAH COSSEL, a citizen of the United States, residing in Wayne township, in the county of Marion and State of Indiana, have invented a new and useful Portable Straw and Hay Stack, of which the following is a specification.

The entire device is represented by a single view, showing a side elevation with the straw-stack elevated and secured ready for operation.

The main frame of the stacker is composed of several sections, as A A' A² A³ A⁴ A⁵. The side rails of these sections form a continuous taper from the base B to the extreme upper end. The side rails A are made fast in the base-piece B, and the joints a' of the sections may be either hinged together, as at L, or secured by plates and bolts, as at K. Between 15 the side rails A is secured a floor, C, for the carrier-bolt F G to slide on. At a convenient distance from the base B is a shaft, E, provided with a sheave or pulley, D, near each end, inside of the side frames A, on which the chains or ropes F of the carrier-belt operate. The shaft D is provided with a pulley (not shown) at one end outside of the side frame A for the purpose of receiving power from a thrashing-machine or engine, and one end of the shaft D may also be provided with a means 20 for attaching it to the tumbling-rod of a horse-power.

The carrier-belt consists of two chains or cords, F, with slats or bars G secured to each at regular intervals. This belt operates on the sheaves or pulleys D below, and on the pulleys H above, as shown.

The upright or hoisting guide consists of two parallel upright standards, M, the lower ends of which are secured in the base W, and firmly braced by the angle-braces O on each side. The upper end of each standard M is provided with a pulley or sheave, P, over which the hoisting-ropes R operate. These 40 hoisting-ropes R have one end made fast to

the side rails of the carrier. These ropes, after passing over the pulley P, are carried to the base of the uprights, and are long enough to permit the carrier to be lowered onto the base W. When the carrier-frame is elevated, as shown, then the ropes R are made fast to cleats J¹, or other fastenings at the base of the guides M. The upper ends of each upright M is provided with an eyebolt, I, or other means for fastening the guy-ropes J J'. These guy-ropes J J' are long enough to fasten to stakes driven into the ground, as at J², or to cleats on the foot of the frame, as at J³, and support the standards M, as shown.

In operation the stacker is carried to the place where the straw or hay is to be stacked, the uprights M are then raised, and the guy-ropes J² J³ made fast. The straw-carrier frame A is then placed between the uprights M and elevated by the ropes R to any desired height and the ropes R made fast.

If power can be furnished from a thrashing-machine or engine to the shaft D by a belt, then the carrier-belt F G may be thus operated to elevate the straw or hay and deposit it on the stack. But in case no power can be obtained from a thrashing-machine or engine, then a horse-power of any kind may be attached to the shaft D and operate the carrier-belt.

What I claim as my invention, and desire to secure by Letters Patent, is—

The hoisting-guides M, with eyebolts I in their tops, combined with the guy-ropes J J', one end of each guy-rope being attached to the lower end of the carrier-frame and the other ends adapted to be secured to the ground or other support, substantially as specified.

In testimony whereof I have signed my name to this specification in the presence of two 85 subscribing witnesses.

AHIJAH COSSEL.
